(57) CLAIM

We claim the ornamental design for a golf club head, as shown and described.

DESCRIPTION

FIG. 1 is a bottom rear perspective view of a golf club head embodying our new design, wherein a portion of the golf club head's sole is encircled by a dotted line to indicate that it is not part of the design.

FIG. 2 is a front elevational view of the golf club head of FIG. 1, wherein the golf club head's face is encircled by a dotted line to indicate that it is not part of the design.

FIG. 3 is a rear elevational view of the golf club head of FIG. 1.

FIG. 4 is a right side elevational view of the golf club head of FIG. 1.

FIG. 5 is a left side elevational view of the golf club head of FIG. 1.

FIG. 6 is a top plan view of the golf club head of FIG. 1.

FIG. 7 is a bottom plan view of the golf club head of FIG. 1.

FIG. 8 is a bottom rear perspective view of a second embodiment of a golf club head embodying our new design, with a portion of the golf club head's sole encircled by dotted lines not being a part of the design.

FIG. 9 is a front elevational view of the golf club head of FIG. 8, with a portion of the golf club head's face encircled by dotted lines not being a part of the design.

FIG. 10 is a rear elevational view of the golf club head of FIG. 8.

FIG. 11 is a right side elevational view of the golf club head of FIG. 8.

FIG. 12 is a left side elevational view of the golf club head of FIG. 8.

FIG. 13 is a top plan view of the golf club head of FIG. 8; and,

FIG. 14 is a bottom plan view of the golf club head of FIG. 8.
